HERMAN C. MAISE AND WILLIAM MARSHALL, OF DETROIT, MICHIGAN, ASSIGNOR TO
BRIGGS MANUFACTURING COMPANY, OF DETROIT, MICHIGAN, A CORPORATION OF
MICHIGAN.

REAR-QUARTER CONSTRUCTION.

Application filed May 11, 1925. Serial No. 29,558.

This invention relates generally to the rear quarter constructions of vehicle bodies of the closed type and consists of certain novel features of construction, combinations and arrangements of parts as will herein-after be described and more fully set forth in the appended claims.

In the accompanying drawings:

Figure 1 is a fragmentary side elevation 10 of a rear quarter construction embodying our invention.

Figure 2 is a fragmentary perspective view thereof.

Figure 3 is a sectional view taken on the 15 line 3—3 of Figure 1.

Figure 4 is a sectional view taken on the line 4—4 of Figure 1.

Figure 5 is a sectional view taken on the line 5—5 of Figure 1.

Figure 6 is a sectional view taken on the 20 line 6—6 of Figure 1.

Figure 7 is a fragmentary perspective view of the upper metal finish strip.

Referring now to the drawings the numerals 1 designates a rear quarter of a vehicle body of the closed type having the spaced pillars 2 and 3 respectively that are secured to the body sills (not shown) and to the side rail 4 of the top and that support a metal panel 5 which preferably has a suitable window opening 6 therein. As shown, the forward pillar 3 constitutes the supporting hinge pillar for the usual swinging door (not shown) and is preferably formed of metal. This pillar 3 is preferably channel-shaped in cross section, the outer flange 7 of the channel being preferably wider than the inner flange 8 and terminating in an inwardly extending flange 9. This flange 9 is relatively narrow and is preferably disposed substantially parallel to the front wall of the pillar. To provide a strong and durable construction, the outer panel 5, extending over the outer face of the pillar 3, has a lateral flange 11 at its forward edge that is preferably welded to the front face 10 of the pillar and is provided at the forward side edge of the window opening 6 with an inwardly extending flange 12 that is substantially parallel to the inwardly extending flange 9 of the pillar and preferably terminates in a forwardly offset substantially L-shaped rabbet 13. For closing the space between this rabbet 13 and the inner flange

8 of the pillar, we preferably provide a metal strip 14 that is preferably secured to the inner flange 8 by means of suitable screws 15. As shown, this strip 14 is preferably provided adjacent to its forward edge with a longitudinally extending bead 16 for holding a bead 17 of a suitable weather strip 18 against the inner flange 8 of the pillar and is preferably provided at its rear edge with a rearwardly opening channel-shaped portion 19 for receiving the forward side edge 65 of a vertically movable window panel 20. This channel-shaped portion 19 seats within the L-shaped rabbet 13 and is secured thereto by suitable tongues 21 that are preferably struck out from the base 22 of the channel 19 and engage the forward flange 23 of the rabbet 13. To provide a neat appearance, a metal finish strip 24 is preferably snapped over the forward and rear edges of the strip 14 so as to conceal the screws 15 and the joint between the strip 14 and the weather strip 18.

Below the window opening 6, the inner flange 8 of the pillar is preferably provided at its rear edge with a laterally extending flange 25 that terminates in a rearwardly extending flange 26, while the strip 14 is preferably provided at its lower end with a channel-shaped extension 27 that is disposed between the flanges 26 and the outer panel 5 and is adapted to receive the forward edge of the glass panel 20 when in lowered position. Any suitable means may be mounted upon the inner panel 28 for raising and lowering the glass window panel 20. As shown, this inner panel 28 is preferably secured at its forward edge to the rearwardly extending flange 26 of the pillar and is provided at its upper edge with an outwardly extending horizontal flange 29. This flange 29 is in substantial alignment with an inwardly extending flange 30 at the lower edge of the window opening 6 in the outer panel as shown in Figure 5 of the drawings and is provided with a suitable slot 31 for receiving a suitable operating lever (not shown) of the usual window lifter mechanism. Any suitable means such as the wood strip 32 may be secured between the depending extension 33 of the flange 30 and the inner face of the outer panel 5 to stiffen and reinforce the latter.

To facilitate the insertion and removal

of the strip 14 and glass panel 20, the horizontal flange 29 terminates short of the forward edge of the inner panel 28 and the lateral flange 25 of the pillar is preferably provided at its upper end with a suitable recess 34 to receive the reduced extension 27 of the strip 14. Thus, with this construction, the glass panel 20 may be readily inserted between the flanges 29 and 30 respectively of the inner and outer panels engaged with a suitable runway (not shown) carried by the rear body pillar 2, whereupon the channel-shaped extension 27 of the strip 14 may be inserted through the recess 34 so that the channel-shaped portions of the strip will receive the forward edge of the glass panel 20. The weather strip 18 is then placed between the strip 14 and inner wall 8 of the pillar 3, whereupon the screws 15 may be engaged with the pillar 3 to hold the strip 14 and weather strip 18 in position.

In order that the weather strip 18 will be effectively held in position against the pillar 3 below the window opening 6, we preferably provide a suitable finish strip 35 that is detachably secured to the flange 8 of the pillar immediately below the strip 14 by means of suitable screws 36 and is preferably provided adjacent to its forward edge with a longitudinally extending corrugation 37 that is in alignment with the corrugation 16 of the strip 14 and that receives the bead 17 of the weather strip. To provide a neat appearance, this strip 35 is also provided at its forward edge with an inwardly extending substantially L-shaped rabbet 38 that receives the forward edges of the usual trimming material 39 forming the interior finish of the body. The upper edges of the trimming material 39 are preferably concealed by suitable depending flange 40 of a finish strip 41 secured to the flange 29 at the upper edge of the inner panel 28.

As shown in Figure 6 of the drawings, the outer panel 5 is secured to the side rail 4 of the top and is preferably provided at the upper edge of the window opening 6 with an inwardly extending flange 42 that terminates in an upwardly offset inverted L-shaped rabbet 43 having the base 44 thereof preferably secured to the lower face of the rail 4. To provide a neat appearance, a metallic header finish strip 45 is provided with an attaching portion 46 that is secured by screws 47 to the inner face of the rail 4 and is provided at the lower edge of the attaching portion with a laterally extending inverted channel-shaped portion 48 that is secured against the base 44 of the rabbet 43 and that is adapted to receive the upper edge of the glass panel 20 when in closed position.

Thus, from the foregoing description, it will be readily apparent that the metal strip 14 cooperates with the outer panel 5 to

close the channel of the pillar 3 to provide a neat as well as a strong and durable construction. Moreover this strip 14 is provided with simple and effective means for holding the weather strip 18 and has a channel-shaped portion for receiving an edge of the glass panel 20. Thus, the strip 14 performs three material functions. Aside from this, the strip 14 serves as an anchor for the finish strip 24. It will also be readily apparent that the finish strip 35 cooperates with the strip 14 to hold the weather strip 18 and is also provided with means for concealing the forward edges of the usual interior trimming material 39. Furthermore the pillar 3 is provided with means to facilitate the insertion or removal of the strip 14 and has a flange 26 that constitutes a bearing for the inner panel 28. Thus, we have provided a neat and compact construction which is exceptionally strong and durable. Moreover the construction may be easily and quickly assembled, consequently the cost of manufacturing the same has been reduced to a minimum.

While it is believed that from the foregoing description the nature and advantages of the invention will be readily apparent, we desire to have it understood that we do not limit ourselves to what is herein shown and described and that such changes may be resorted to when desired as fall within the scope of what is claimed.

What we claim as our invention is:

1. In a vehicle body construction, the combination with a pillar, a weather strip at one side of the pillar, and a window panel at another side of the pillar, of a metal strip having a portion holding the weather strip and having a channel-shaped portion for receiving an edge of the window panel, means for securing the metal strip to the pillar, and a finish metal strip secured to the strip aforesaid and concealing the securing means and the joint between the metal strip and weather strip.

2. In a vehicle body, the combination with a metal panel having a window opening, and a removable window panel for closing said opening, of a pillar secured to said metal panel and having a lateral flange provided with a recess, and a removable metal strip carried by the pillar and having an extension below the window opening and adapted to be moved through the recess aforesaid to permit the removal of the window panel.

3. In a vehicle body, the combination with a rearwardly opening channel-shaped pillar, of a metal panel secured to the outer face of said pillar, said panel having a window opening therein and an inwardly extending lateral flange at one edge of said opening, said flange being disposed substantially parallel to the base of said channel pillar

and having a forwardly extending lateral flange disposed substantially parallel to said panel, a metal strip secured to the inner face of said pillar and having a portion substantially parallel to the forwardly extending lateral flange aforesaid, and a closure for said window opening movable between said forwardly extending flange and the portion aforesaid of said strip.

10 4. In a vehicle body construction, the combination with a pillar, of a metal panel secured to the outer face of said pillar, said panel having a window opening therein, and an inwardly extending lateral flange at one 15 edge of said opening, a metal strip secured at its forward edge to the inner face of said pillar and having a substantially channel-shaped portion at its rear edge secured to said inwardly extending lateral flange, and 20 a closure for said window opening slidably mounted in the channel-shaped portion of said strip.

5. In a vehicle body construction, the combination with a pillar, of a metal panel secured to the outer face of said pillar, said panel having a window opening therein and an inwardly extending lateral flange at one edge of said opening, said flange being disposed substantially parallel to a wall of said 30 pillar and having a forwardly extending lateral flange disposed substantially parallel to said panel, said forwardly extending flange having an inwardly extending lateral flange, a metal strip secured to the inner face 35 of said pillar and having a portion substantially parallel to said forwardly extending flange, and a closure for said window opening movable between said forwardly extending flange and said strip, the portion aforesaid of said strip being secured to the last 40 mentioned inwardly extending lateral flange.

6. In a vehicle body construction, the combination with a pillar, of a metal panel secured to the outer wall of said pillar, said panel having a window opening therein and an inwardly extending flange at an edge of said opening, said flange being provided at its inner edge with a substantially L-shaped rabbet, and a separate metal strip secured to the inner wall of said pillar and having a 50 channel-shaped portion secured in the rabbet aforesaid, and a closure for said window opening movable in the channel-shaped portion of said strip.

55 7. In a vehicle body construction, the combination with a pillar, and a weather strip extending longitudinally thereof, of a panel secured to the outer face of said pillar having a window opening therein, and an inwardly extending lateral flange at one edge of said opening, a metal strip closing the space between said inwardly extending lateral flange and said pillar, said metal strip having a portion overlapping and holding said weather strip against said pillar and having

a channel-shaped portion secured to said inwardly extending flange, and a closure for said window opening movable in the channel-shaped portion of said metal strip.

8. In a vehicle body, the combination with 70 a metal panel, of a pillar secured to said panel and having a longitudinally extending forwardly opening substantially L-shaped rabbet, a weather strip extending longitudinally of said rabbet, trimming material extending over said metal panel, and a metal finish strip extending longitudinally of and secured to said pillar, said finish strip having a portion holding the weather strip in said rabbet and having a substantially L-shaped rabbet portion receiving an edge of the trimming material, the arrangement being such that said finish strip and trimming material close the rabbet in said pillar.

9. In a vehicle body, the combination with 85 an outer panel, of a pillar secured to said panel and having a longitudinally extending substantially L-shaped rabbet, a weather strip in said rabbet, one edge of said rabbet having a lateral flange, an inner panel secured to said lateral flange, trimming material extending over said inner panel, and a metal finish strip secured in said rabbet, said finish strip having a portion holding the 90 weather strip in the rabbet and having another portion overlapping and concealing the adjacent edges of said trimming material.

10. In a vehicle body, the combination 100 with spaced inner and outer panels, said outer panel having a window opening therein, and a removable closure for said opening located between said panels, of a pillar between said panels, said pillar having a lateral flange below said opening secured to one 105 of said panels, and a metal strip detachably secured to said pillar and having a channel-shaped portion between said panels receiving an edge of said closure, the lateral flange of said pillar having a recess at its upper end to facilitate the removal of said closure and strip.

11. In a vehicle body construction, the combination with a top frame member, of a metal panel secured to the outer face thereof 115 and having a window opening therein, and a flange projecting inwardly from said panel at the upper edge of said opening and having an inwardly extending inverted substantially L-shaped rabbet, the base of said rabbet being secured to the lower face of said frame member, and a metal header having an inverted channel-shaped portion secured in said rabbet, one wall of said channel portion having a return-bent portion extending upwardly at substantially right angles to the base of said rabbet and secured to the inner face of said frame member.

12. In combination, a pillar having a 120 substantially L-shaped rabbet, one wall of

said rabbet having a rearwardly extending lateral flange, a panel secured to said lateral flange, trimming material extending over said panel to a point in substantial alignment with the forward wall of said pillar, and a finish strip secured in said rabbet having a lateral flange projecting inwardly beyond the panel, said inwardly extending flange having a lateral projection overlapping and 10 concealing the adjacent free edges of said trimming material.

13. In a vehicle body, the combination with spaced inner and outer panels, of a pillar disposed between and secured to said 15 panels, said pillar having a substantially L-shaped rabbet, a metal substantially channel-shaped finish strip secured in said rabbet, and trimming material extending over the inner panel having the edges thereof adjacent to said pillar received in and concealed by the channel of said finish strip.

14. In a vehicle body, the combination with a pillar, of a metal panel secured to the outer face of said pillar, said panel having 25 a window opening therein and an inwardly extending lateral flange spaced from said pillar, a closure for the window opening, and a metal strip closing the space between said pillar and flange, said metal strip being 30 secured to said pillar and having a channel-shaped portion receiving an edge of said closure.

15. In a vehicle body, the combination with a pillar, and a weather strip extending 35 longitudinally thereof, of a metal panel secured to the outer face of said pillar, said panel having a window opening therein and an inwardly extending lateral flange at one edge of said opening, a vertically movable 40 closure for said window opening, and a metal strip extending longitudinally of and secured to the inner face of said pillar, said strip holding the weather strip against the pillar and having a portion at its rear edge 45 secured to the lateral flange of said panel, the arrangement being such that a channel is provided between a portion of said flange and a portion of said metal strip for receiving and guiding an edge of said closure.

16. In combination, a pillar having an inwardly extending lateral flange, a weather strip extending longitudinally of said pillar, an outer panel secured to said pillar having 55 a window opening therein and an inwardly extending lateral flange at one edge of said opening, a closure for said opening, an inner panel secured to the inwardly extending lateral flange of said pillar below said window opening, trimming material extending over 60 said inner panel, and means for holding said

weather strip in position on said pillar, said means including a metal strip secured to the pillar below the window opening, said metal strip having a portion overlapping a portion of said weather strip and having another portion extending inwardly beyond 65 the inner panel, said last mentioned portion having a flange projecting rearwardly over and concealing the adjacent free edges of said trimming material, and a second metal strip secured to the pillar at a point above the first mentioned metal strip, said second metal strip having a portion overlapping the weather strip and having a channel-shaped portion receiving an edge of said closure. 70

17. In a vehicle body construction, the combination with a pillar, and a weather strip extending longitudinally thereof, of a panel secured to said pillar having a window opening therein, a plate secured to the 75 pillar having a longitudinally extending bead at one edge receiving a portion of said weather strip for holding the same against said pillar, the opposite end of said plate terminating in a channel-shaped portion and secured to said panel, and a closure for said window opening movable in the channel-shaped portion of said plate. 80

18. In a vehicle body construction, the combination with a pillar, a weather strip at 90 one side of the pillar and extending longitudinally thereof, and a window panel, of a metal strip secured to said pillar having a longitudinally extending corrugation adjacent one edge thereof engageable with the 95 upper portion of said weather strip to hold the same against said pillar, said strip further formed with a channel-shaped portion receiving an edge of said window, and a finish strip secured to said pillar formed 100 with a longitudinally extending corrugation in alignment with the corrugation aforesaid, and engageable with the lower portion of the weather strip to effectively hold the same in position against said pillar. 105

19. In a vehicle body construction, the combination with a metal panel, of a pillar secured to said panel, a weather strip extending longitudinally of said pillar, trimming material extending over said metal panel, and a metal finishing strip secured to said pillar having a longitudinally extending corrugation for receiving a portion of said weather strip and having a laterally extending rabbet for receiving an edge of the trimming material. 110

In testimony whereof we affix our signatures.

HERMAN C. MAISE.
